HEATER FOR FLUIDS

Marion W. Barnes, Chicago, Ill., assignor to Universal Oil Products Company, Chicago, Ill., a corporation of Delaware

Application January 26, 1942, Serial No. 428,239

5 Claims. (CL 122—356)

The invention is directed to an improved form of heater for fluids which is particularly advantageous as applied to heating hydrocarbons to the high temperatures required for their thermal or catalytic conversion, but which will also be found useful in numerous other applications wherein it is desired to heat one or more streams of fluid with relatively high rates of heat input.

The heater herein provided is of the general type employing a plurality of separately fired cells with tubular fluid conduits disposed in each cell to receive direct radiant heat from the flames and hot combustion gases passing therethrough and from refractory walls of the heater over which said flames and hot combustion gases are passed.

The features and advantages of the invention will be apparent to those familiar with the art from an inspection of the accompanying diagrammatic drawing and the following description thereof.

The single figure of the drawing represents a cross-sectional elevation of one specific form of the heater provided by the invention.

Referring to the drawing, the heater here illustrated comprises substantially vertical refractory side walls 1 and 2, inwardly and upwardly sloping refractory walls 3 and 4 which connect walls 1 and 2, respectively, with the other vertical refractory outer walls 5 and 6, a floor 7, and end walls not shown.

Interior refractory walls 8 and 9, spaced from each other and from the side walls 1 and 2, are provided within the heater and extend from the floor to a level adjacent the upper extremity of walls 1 and 2.

The space within the heater between walls 1 and 8 comprises a combustion and radiant heating zone or fired cell 10, and a separately fired combustion and radiant heating zone or cell 11 is defined between walls 2 and 9. A centrally disposed cell, comprising the independently fired combustion and radiant heating zones 12 and 13, is provided between walls 8 and 9.

A bank 14, comprising, in the case illustrated, a single vertical row of horizontally disposed tubular fluid conduits 15, is located within cell 10 adjacent the interior surface of wall 1. Another bank 16, comprising in this instance a single vertical row of horizontally disposed tubes 17, is located in cell 11 adjacent the inner surface of wall 2. Another bank 18, comprising, in the case illustrated, two vertically parallel rows of horizontally disposed tubes 19, is located substantially midway between walls 8 and 9 in the

central cell. Another bank 20, comprising in this instance a single row of horizontally disposed tubes 21, is located in the upper portion of the heater adjacent the inner surface of wall 3 and a similar bank 22 of tubular fluid conduits 23 is disposed in the upper portion of the heater adjacent the inner surface of wall 4. Still another bank 24, comprising a plurality of superimposed horizontal rows of horizontally disposed tubes 25, is located in the fluid heating zone 26 defined between walls 5 and 6. A flue 27 leading to a suitable stack 28 is provided above zone 26.

The entire furnace structure is mounted upon a suitable foundation which, in this instance, comprises a vertical wall 29 disposed beneath each of the walls 1, 2, 3 and 4, a floor 30, disposed beneath and spaced from the refractory floor 7, and suitable footings, not illustrated. Burner compartments 31, 32, 33 and 34, individual to the respective combustion and heating zones 10, 11, 12 and 13, are provided beneath floor 7 and between the walls 29 and suitable partitions 35 and 36 are provided to separate the individual burner compartments from each other.

A horizontal row of burners, one of which is indicated at 37, is provided within burner compartment 31 and these burners communicate with combustion and heating zone 10 through firing ports 38 provided in floor 7 adjacent the lower end of wall 8. Fuel is supplied to each of the burners 37 through line 39 and valve 40 and air is admitted in regulated amounts to burner compartment 31 by the adjustment of a suitable damper 41 provided at the mouth of opening 42 through the adjacent wall 29. The air thus admitted to compartment 31 passes through burners 37 to mix with the fuel and form a combustible mixture which is burned in zone 10 adjacent the surface of wall 8. The flames and hot combustion gases issuing from burners 37 and burner ports 38 are directed upwardly at an angle against and over the surface of wall 8, heating the latter to a highly radiant condition and direct radiant heat is transmitted from wall 8 and from the flames and hot combustion gases passing thereover to one side of the tubes 15 of bank 14. Reflected radiant heat is transmitted from wall 1 to the opposite side of these tubes.

A firing arrangement similar to that above described with the elements thereof designated by the same reference numerals 37 and 42 inclusive is provided for cell 11, which is fired independently of cell 10 and wherein direct radiant heat is transmitted from the hot refractory surface of wall 8 and from the flames and hot

combustion gases passing thereover to one side of the tubes 17 to bank 16. The opposite side of these tubes is heated by reflected radiant heat from wall 2.

Another horizontal row of burners, one of which is indicated at 43, is provided in burner compartment 33 for directing flames and hot combustion gases through firing ports 44, disposed in floor 7 adjacent the base of wall 8, upwardly into combustion and heating zone 12 over the surface of wall 8 facing tube bank 18, heating the latter to a highly radiant condition. Fuel is supplied to each of the burners 43 through a line 45 and a valve 46 and air for combustion of the fuel is admitted in controlled amounts, by the adjustment of damper 47, to burner compartment 33 through openings 48 and 49 in walls 29. A similar firing arrangement, wherein corresponding portions are indicated by the same reference numerals 43 to 49 inclusive, is provided for combustion and heating zone 13 to direct flames and hot combustion gases upwardly over the surface of wall 9 facing tube bank 18.

The tubes in the opposite rows of bank 18 are arranged in staggered formation and are so spaced that each tube is heated on one side by direct radiation from the surface of wall 8 and from the flames and hot combustion gases passing thereover and on its opposite side from the surface of wall 9 and the flames and hot combustion gases passing thereover. The tubes in the right-hand row of bank 18 are, of course, partially shielded from radiant heat transmitted from the wall 8 and from the flames and hot combustion gases in zone 12, while the tubes in the left-hand row of bank 18 are partially shielded from radiant heat transmitted from wall 9 and from the flames and hot combustion gases passing through zone 13. Thus, by independent firing of zones 12 and 13, a considerable degree of independent control may be exerted over the rates of heat transmission obtained in the right and left-hand rows of bank 18. The heating conditions employed in zones 10 and 11 and the rates of heating obtained in banks 14 and 16 are made entirely independent of each other and of the heating conditions employed in zones 12 and 13 by the provisions for independently firing each of the zones 10 and 11. Thus, an unusually high degree of flexibility is provided in this heater and by the selection of suitable specific paths of flow through the tube banks and a suitable sequential or parallel arrangement of the tube banks in said flow, a wide variety of heating curves is obtainable for the fluid undergoing treatment, and the type of heat treatment desired may be selected to suit requirements. When desired, it is also easy to obtain either a different type of heat treatment or substantially the same heat treatment or two or more separate streams of fluid with the heater herein provided.

Combustion gases which have given up a substantial portion of their heat to the respective tube banks 14, 16 and 18 are discharged from each of the independently fired combustion and heating zones 10, 11, 12 and 13 into the space between walls 3 and 4 and supply both radiant and convection heat to the tubular elements of banks 20 and 22. The tubes of these banks receive direct radiant heat on one side from the hot combustion gases and receive reflected radiant heat on their opposite sides from the respective walls 3 and 4. Heating conditions ob-

tained in bank 20 are, of course, influenced to a greater extent by the combustion gases from zones 10 and 12 than those from zones 11 and 13, while the heating conditions obtained in bank 22 are influenced to a greater extent by the combustion gases from zones 11 and 13 than from zones 10 and 12, so that a considerable degree of independent control is also obtainable over the heating conditions employed in bank 20 as compared with that obtained in bank 22 and vice versa.

The total combustion gases from zones 10, 11, 12 and 13, after supplying heat to the tubes of banks 20 and 22, pass upwardly through fluid heating zone 26 in intimate contact with the tubes of bank 24 in this zone and supply a considerable portion of their residual heat thereto. The combustion gases are thence directed through flue 27 to stack 28.

The invention is not limited to any specific path of flow of fluid through the various tube banks nor to any specific sequence of flow through the several banks. Ordinarily, adjacent tubes in each bank will be connected in series at their ends by suitable return bends or headers, not illustrated, but it is also within the scope of the invention to connect portions or all of the tubes in any bank for parallel flow or to connect several banks for the parallel flow of separate streams of the same or different fluid therethrough. It is also within the scope of the invention to dispose the tubular elements of any or all of the various banks adjacent the side and interior walls in a vertical rather than a horizontal position and the tubes in either or both of the banks adjacent the sloping walls of the heater may extend lengthwise from adjacent the top to adjacent the bottom of the sloping wall rather than from end to end thereof. As previously mentioned, a wide variety of advantageous flow arrangements are possible in the improved form of heater herein provided and may be selected within the skill of one familiar with the art and correlated with the firing conditions employed in the independently fired combustion and heating zones to suit requirements.

Although the specific form of heater illustrated in the drawing is up-fired with a general upward flow of combustion gases throughout the heater, it is entirely within the scope of the invention to invert the furnace structure and fire in a downward direction with a general downward flow of combustion gases through the heater.

The invention also contemplates a two row arrangement instead of a single row of tubes in any or all of the banks 14, 16, 20 and 22 and, when desired, a single row of tubes or more than two rows of tubes (usually three or four rows) may be employed in bank 18 instead of the two row arrangement shown in the drawing. These and numerous other variations from the specific structure illustrated will be evident to one familiar with the art.

I claim as my invention:

1. A heater for fluids comprising, in combination, refractory side and end walls, a floor and a roof, a pair of substantially vertical, refractory, interior walls spaced from each other to provide a central radiant heating cell therebetween and spaced from said side walls to provide a side radiant heating cell between each of said interior walls and the adjacent side wall, a substantially vertical bank of tubular fluid conduits disposed substantially midway between said interior walls in the central cell, a substantially

vertical bank of tubular fluid conduits disposed in each of the side cells adjacent one of said refractory walls thereof, independent firing means for each of said cells, means for directing flames and hot combustion gases from the firing means for said side cells upwardly therethrough over the surface of that refractory wall thereof opposite said tube bank disposed therein, means for directing flames and hot combustion gases from the firing means for said central cell upwardly cover the refractory surfaces of said central walls facing said tube bank in the central cell, a convection heating zone above and in alignment with said central cell, heating tubes disposed in said convection zone, and means for passing combustion gases from said side cells and central cell through the convection heating zone.

2. A heater for fluids comprising, in combination, refractory side walls, a pair of substantially vertical refractory interior walls spaced from each other to provide a central radiant heating cell therebetween and spaced from said side walls to provide a side radiant heating cell between each of said interior walls and the adjacent side wall, a substantially vertical bank of tubular fluid conduits disposed in said central cell substantially midway between the interior walls, a substantially vertical bank of tubular fluid conduits disposed adjacent the side wall in each of said side cells, burner means disposed adjacent one end and on opposite sides of each of the central walls for directing flames and hot combustion gases thereover, a convection heating zone in vertical alignment with said central cell and heating tubes disposed therein, and means for passing combustion gases from said side cells and central cell through the convection heating zone.

3. A heater for fluids comprising, in combination, a pair of substantially vertical refractory side walls and a pair of substantially vertical refractory end walls defining the lower portion of the heater, refractory sloping walls extending inwardly and upwardly from the side walls to other substantially vertical refractory side walls between which is disposed a fluid heating zone of smaller cross-sectional area than that of said lower portion of the furnace, a pair of substantially vertical refractory interior walls spaced from each other within said lower portion of the heater to provide a central radiant heating cell

therebetween and spaced from the first named side walls to provide a side radiant heating zone between each of said interior walls and the adjacent side wall, a substantially vertical bank of tubular fluid conduits disposed in said central cell substantially midway between the interior walls, a bank of tubular fluid conduits disposed in each of said side cells adjacent the first named refractory wall thereof, a bank of tubular fluid conduits disposed adjacent and substantially parallel to each of said sloping walls, a bank of tubular fluid conduits disposed within said fluid heating zone, burners disposed adjacent the base and on opposite sides of each of the interior walls for directing flames and hot combustion gases upwardly over the opposite surfaces thereof through said cells, said fluid heating zone being in direct communication with each of said cells through the space defined between said sloping walls.

4. A heater for fluids comprising a first pair of spaced, substantially vertical refractory walls, a second pair of substantially vertical refractory walls spaced from each other and disposed between and spaced from the first-named walls to form an intermediate heating cell and an additional heating cell on each side of the intermediate cell, a bank of heating tubes in said intermediate cell substantially midway between said second pair of walls, heating tubes in each of said additional cells adjacent one of said first pair of walls, and burner means disposed adjacent an end and on opposite sides of each of the walls of said second pair for directing hot combustion products over both sides of each of the last-named walls.

5. In a furnace having refractory side walls, the combination of a pair of substantially vertical refractory interior walls spaced from each other to form a central heating zone therebetween and spaced from the side walls to form a side heating cell between each of the interior walls and the adjacent side wall, a bank of heating tubes in said central cell substantially midway between said interior walls, heating tubes in each of said side cells adjacent one of said side walls, and burner means disposed adjacent an end and on opposite sides of each of said interior walls for directing hot combustion products over both sides of each of the interior walls.

MARION W. BARNES.
